TION OF DELAWARE

THERMOSTATICALLY-CONTROLLED VALVE MECHANISM

Application filed October 30, 1926. Serial No. 145,345.

This invention relates to thermostatically controlled valve mechanism and particularly to mechanism of this character adapted for controlling the circulation of cooling medium through the cooling systems of internal combustion engines. The invention is capable of embodiment both in thermostatically controlled valve mechanism of the choker type wherein the opening and closing of the valve determines the quantity of cooling medium in circulation and in thermostatically controlled valve mechanism of the by-pass type wherein the opening and closing of the valve determines the path of circulation or flow of said cooling medium.

An object of this invention is to provide a simplified thermostatically-operated valve unit composed of light but relatively strong and rigid parts which may be inexpensively formed and assembled.

Another object of this invention is to provide a device of the character described with novel means for mounting the thermostat.

Further objects of the invention will appear as the description of the invention proceeds.

The invention is capable of receiving a variety of mechanical expressions, one of which is shown on the accompanying drawings, and it is to be expressly understood that the drawings are for purposes of illustration only and are not to be construed as a definition of the limits of the invention, reference being had to the appended claims for that purpose.

Referring in detail to the drawings wherein the same reference characters are employed to designate corresponding parts in the several figures

Fig. 1 is an axial section on an enlarged scale of an embodiment of the present invention.

Fig. 2 is a transverse section on the line 2—2 of Fig. 1.

Fig. 3 is a perspective view of the cage-like support for the thermostat.

Fig. 4 is a plan view on a smaller scale of a blank from which the support of Fig. 3 may be formed, and

Fig. 5 is a plan view on a small scale of the valve seat ring.

In the form shown in Fig. 1, 1 is a thermostat of any suitable character and possessed of any suitable physical characteristics, being shown as provided with a deeply corrugated, highly flexible, expansible and collapsible tubular metal wall, preferably of resilient metal, connected at its opposite ends in any suitable way, as by soldering or brazing, to a stationary end wall 2 and a movable end wall 3. The stationary end wall 2 is provided with an exteriorly threaded boss 4 which may also contain the filling aperture 5, shown as sealed by a stopper 6 and solder 7. The movable end wall 3 is provided exteriorly with a stem 8, integral therewith or suitably attached thereto, said stem being threaded as shown at 9 for the attachment of a valve member thereto. Interiorly of the thermostat, said movable end wall 3 is shown as provided with a tubular stop 10, integral therewith or suitably attached thereto, for limiting the contractive movement of the thermostat. The thermostat so provided is charged with a thermosensitive fluid of any suitable character.

In conformity with the present invention said thermostat is mounted in operative position by means of a combined cage and support 11 one form of which is shown in Fig. 3. As here shown said combined cage and support is composed of a base portion 12 provided with an aperture 13 designed to receive the threaded boss 4 on the stationary end wall 2 of the thermostat and a plurality of axially extending elements or arms 14 bent at substantially right angles to said base portion 12, and flanged outwardly as shown at 15 at the extremity of each of said arms. Each of said arms is also preferably reduced in width adjacent its extremity as shown at 17 for a purpose to be explained, said reduced portions 17 being preferably connected to the main portions of the arms 14 by beveled or inclined surfaces 18. The combined support and cage so formed is preferably stamped out of and bent up from sheet metal, a suitable blank therefor being illustrated at 19 in Fig. 4. While the combined cage and support is

thus preferably formed from a unitary blank of the character shown in Fig. 4, it is to be expressly understood that the invention in its broader features is not restricted thereto, 5 as the same might be built up of two or more separately formed strip-like sections which are crossed at their base portions. Also, while the illustrated embodiment includes four arms, it is to be expressly understood 10 that the invention is not restricted thereto as a fewer or larger number of arms may be provided, if desired.

The combined cage and support is retained in assembled relation with the thermostat by means of a nut 20 threaded onto the boss 4 and clamping the base portion of the combined cage and support fixedly to the end wall 2 of the thermostat, in which position the plurality of arms 14 extend axially of the thermostat and surround the same with sufficient clearance to permit the free expansion and contraction of said thermostat.

The combined cage and support 11 is assembled with a valve seat ring 21, preferably of the character illustrated in Fig. 5. As here shown, said ring is stamped out of sheet metal and its inner periphery is provided with a plurality of notches 22, conforming in number with the arms 14 of the combined cage and support, said notches being of a width to snugly receive the reduced upper ends 17 of said arms 14. The combined cage and support may be assembled with said 25 valve seat ring 21 by pressing inwardly the free ends of the arms 14 so that they may pass through the central aperture of the valve seat ring 21. The free ends of the arms 14 are then engaged in the notches 22 and relative 30 rotation between the valve seat ring and the combined cage and support is thereby prevented.

Means are also provided for clamping the valve seat ring 21 against the underside of 45 the outwardly projecting flanges 15 formed on the free extremities of the arms 14. In the form shown said clamping means is composed of a pair of metal strips 23 and 24, preferably formed from sheet metal and 50 united to embrace the valve stem 8, as by rivets or screws 25. Preferably each of said strips 23 and 24 is bent intermediate its length into substantially semi-circular form as shown at 26, or given any other suitable 55 conformation, so that they are adapted to embrace and guide the valve stem 8 in its movements. While it is preferred to bend both of said strips as shown, so that they are formed from duplicate blanks, said strips may be so 60 designed that only one of them is bent, or their bends may be unequal, to embrace the valve stem. Each of said strips 23 and 24 is also provided with hook-shaped ends 27 so 65 that when the two strips are assembled as illustrated in Fig. 2, the hook-shaped portions

at each end of the assembled transverse member will embrace between them the reduced portions 17 of a pair of opposed arms 14 of the combined cage and support. The width of the hook-shaped ends of said members 23 and 24 is such as compared to the distance between the upper or inner edges of the inclined or beveled faces 18 and the underface of the valve seat ring 21 that said inclined or beveled surfaces 18 will cam the sections 23 and 24 into firm contact with the valve seat ring 21, when said sections are united by the rivets or screws 25, and thereby the valve seat ring 21 will be firmly and rigidly clamped between a pair of opposed flanges 15 and the portions 28 of the hook-shaped ends 27 which lie exteriorly of the cage arms 14. While only a single combined transverse member 23, 24 has been illustrated, a second similar member may also be employed, by suitably varying the width of said transverse members, so as to constitute a right angularly disposed transverse member connecting the second pair of arms shown in Fig. 2.

A valve member 29 of any suitable character is mounted on the outer threaded end 9 of the valve stem 8. In the form shown, said valve member 29 is provided with a central internally threaded hub 30 and a peripheral 95 axially directed flange 31 which is adapted to engage or seat on the valve seat ring 21 exteriorly of the periphery of the flanges 15.

In assembling the thermostatically operated valve unit embodying the present invention, a thermostat of any suitable construction and characteristics, such as illustrated on the drawing, having been provided, and a blank 19 having been cut from sheet stock and bent into the form shown in Fig. 3:—the thermostat is assembled with the cage-like support by introducing the threaded boss 4 through the aperture 13 in the base of said cage-like support and then firmly clamping said support to the stationary end wall 2 of the thermostat by threading the nut 20 onto the threaded boss 4. The arms 14 of the support are then collapsed sufficiently to introduce them into the central aperture of the valve seat ring 21 and said arms are then expanded to engage their reduced portions 17 in the notches 22 in the inner periphery of said ring. Said valve seat ring is then fixedly clamped against the underfaces of the flanges 15 by assembling a pair of members 23 and 24 around the valve stem 8, with the hooked ends 27 embracing a pair of opposed arms 14 at their reduced portions 17, and then uniting said sections 23 and 24, as by rivets or screws. As heretofore explained, the inclined or beveled surfaces 18 on the arms 14 cam the transverse members 23 and 24, as they are united, into clamping engagement with the valve seat ring 21, and at the same time said combined trans-

verse member 23, 24 acts as a brace to retain the opposed arms 14 engaged thereby in their interlocked relation with the slots 22 in the valve seat ring 21. When so assembled, 5 moreover, the sections 23, 24 of said combined transverse member, owing to the presence of the curved intermediate portions 26, embrace the valve stem 8 to act as a guide therefor and, by preference, the parts are so designed 10 that the inner edge 32 of said transverse member 23, 24 is properly positioned to act as a stop, for the expansive movement of the thermostat, by coaction with the movable end wall 3 or a part suitably mounted thereon 15 or on the valve stem. It will therefore be perceived that the combined transverse member 23, 24 performs a plurality of functions:—it locks the valve seat ring against the flanges 15, it locks a pair of opposed arms 20 14 in their spaced apart position and interlocked with the slots 22 in said valve seat ring, it serves as a guide for the valve stem, and it may also act as a stop to limit the expansive movement of the thermostat.

25 The valve member is then assembled with the combined thermostat and support by threading the same onto the end of the valve stem 9 until the seating flange 31 engages the valve seat ring 21, and preferably the valve 30 disk is advanced a further distance onto the valve stem 9 so as to withdraw the tubular support 10, when such is used, from contact with the stationary end wall 2 of the thermostat. The valve member is then locked to 35 the valve stem 8 in any suitable way, as by drilling a hole through the hub 30 and stem 9 and inserting a cotter pin 33 therein.

As heretofore pointed out, the thermostat may be of any suitable construction and 40 possessed of any suitable characteristics. Preferably it is charged with a thermosensitive fluid at a pressure below atmospheric, at normal temperature, so that at all temperatures below that at which the thermostat is 45 designed to operate, there is an excess exterior pressure acting on the thermostat and tending to collapse the same. In the event of leakage and the consequent equalization of the interior and exterior pressure, therefore, 50 the thermostat will tend to expand and withdraw the valve member from its seat.

It will therefore be perceived that a simple 55 thermostatically operated valve unit has been provided wherein the thermostat is mounted and protected by means of a cage-like support which may be blanked out of and bent up from sheet metal. Said cage-like support is also interlocked and carried by a valve seat ring which may also be blanked out of sheet 60 metal. Moreover, the cage-like support and valve seat ring are interlocked against both radial and axial displacement by clamping elements which may also be blanked out of and bent up from sheet metal and which elements, when assembled, give strength and

rigidity to the structure and also serve the functions of a valve stem guide and a stop for the thermostat when desired. The thermostatically operated valve unit is therefore composed of a few readily manufactured parts which are easy to produce and assemble. While it is preferred to make the component parts of sheet metal as heretofore described, such is not essential. It is also to be expressly understood that the invention is not limited to the use of any particular construction of thermostat, as the manner of constructing and charging the thermostat forms no part of the present invention. Also while the ring 21 has been shown as constituting a seat for the valve member, the valve seat may be otherwise provided within the broader aspects of this invention.

While the embodiment of the invention illustrated on the drawing has been described with considerable particularity, it is to be expressly understood that the invention is not restricted thereto as the same is capable of receiving a variety of mechanical expressions, some of which will now readily suggest themselves to those skilled in the art, while changes may be made in the details of construction, arrangement and proportion of parts without departing from the spirit of this invention. Reference is therefore to be had to the claims hereto appended for a definition of said invention.

What is claimed is:

1. In a device of the character described, in combination with a thermostat and a valve member operatively connected thereto, a thermostat support having a plurality of axially extending arms, and a ring notched to receive and retain said arms.
2. In a device of the character described, in combination with a thermostat and a valve member operatively connected thereto, a support having a base secured to said thermostat and a plurality of arms extending axially therefrom, a ring provided with notches to receive said arms, and means mounted on said arms to lock said ring in said notches.
3. In a device of the character described, in combination with a thermostat and a valve member operatively connected thereto, a thermostat support having a plurality of arms flanged at their outer extremities, and a valve seat ring retained against the rear faces of the flanges of said arms.
4. In a device of the character described, in combination with a thermostat and a valve member operatively connected thereto, a support for said thermostat having a plurality of arms provided with flanges at their outer extremities, a ring provided with notches, and means to lock said arms in said notches with said flanges in contact with said ring.
5. In a device of the character described, in combination with a thermostat and a valve member operatively connected thereto, a sup-

port for said thermostat having a plurality of arms, a notched ring surrounding said arms, and means for locking said arms in the notches of said ring, including a transverse member disposed between opposed arms and preventing the inward movement of the same.

6. In a device of the character described, in combination with a thermostat and a valve member operatively connected thereto, a support for said thermostat having a plurality of arms, a notched ring surrounding said arms, and means for locking said arms in the notches of said ring including a transverse member disposed between opposed arms and positioned to limit the movement of the thermostat.

7. In a device of the character described, in combination with a thermostat and a valve stem operatively connected thereto, a support for said thermostat having a plurality of arms, a notched ring surrounding said arms, and means for locking said arms in the notches of said ring including a transverse member disposed between opposed arms and embracing and guiding said stem.

8. In a device of the character described, in combination with a thermostat and a valve stem operatively connected thereto, a support for said thermostat having a plurality of arms, a ring provided with notches in its periphery, and means for locking opposed arms in said notches including a transverse member secured to said arms, said member being composed of sections united to embrace said valve stem.

9. In a device of the character described, in combination with a thermostat and a valve stem operatively connected thereto, a support for said thermostat having a plurality of arms, a ring provided with notches in its periphery, and means for locking opposed arms in said notches including a transverse member secured to said arms, said member including sheet metal sections bent intermediate their ends to provide a valve stem guide.

10. In a device of the character described, in combination with a thermostat and a valve member operatively connected thereto, a support for said thermostat having a plurality of arms, a ring provided with notches in its periphery, and means for locking opposed arms in said notches including a transverse member secured to said arms, said transverse member including a plurality of sections bent up from sheet metal and provided with hook-like ends embracing opposed arms of said support and retaining the same in interlocking relation with said notches.

11. In a device of the character described, in combination with a thermostat and a valve member operatively connected thereto, a support for said thermostat having a plurality of separate arms provided with flanges at their outer extremities, a ring surrounding

said arms, and means for locking said ring against the underfaces of said flanges, said means including a transverse member composed of sections clamped about opposed arms of said support.

12. In a device of the character described, in combination with a thermostat and a valve member operatively connected thereto, a support for said thermostat having a plurality of arms provided with flanges at their outer extremities, a ring having notches in its inner periphery surrounding said arms, and means for locking said arms in said notches with said ring engaged with said flanges, said means including a transverse member composed of sections united to form a brace between the opposed arms of said support.

13. In a device of the character described, in combination with a thermostat and a valve member operatively connected thereto, a support for said thermostat having a plurality of separate arms provided with flanges at their outer extremities, said arms being reduced in width adjacent said flanges and having beveled faces joining said reduced portions with the main portions of said arms, a ring, and a transverse member mounted on opposed arms and coacting with said beveled faces to force said ring into firm contact with said flanges.

14. In a device of the character described, in combination with a thermostat and a valve member operatively connected thereto, a support for said thermostat provided with a plurality of arms, a ring provided with notches to receive said arms, and a transverse member for interlocking said arms in said notches, said transverse member cooperating with said arms to lock said ring against axial displacement.

15. In a device of the character described, in combination with a thermostat and a valve member operatively connected thereto, a support for said thermostat provided with a plurality of arms, a ring provided with notches to receive said arms, and a transverse member for interlocking said arms in said notches, said transverse member being composed of sections connected to opposed arms of said support and positioned intermediate their length to act as a stop for the expansive movement of the thermostat.

16. In a device of the character described, in combination with a thermostat and a valve member operatively connected thereto, a support for said thermostat provided with a plurality of arms flanged at their extremities, a ring provided with notches to receive said arms, and a transverse member for interlocking said arms in said notches, said member being composed of sections embracing opposed arms of said support and clamping said valve seat ring against said flanges.

17. In a device of the character described,

in combination with a thermostat and a valve stem operatively connected thereto, a support for said thermostat having a plurality of arms, a ring provided with notches in its periphery, and means for locking opposed arms in said notches including a transverse member secured to said arms.

18. In a device of the character described, in combination with a thermostat and a valve stem operatively connected thereto, a support for said thermostat having a plurality of arms, a ring provided with notches in its periphery, and means for locking opposed arms in said notches including a transverse member secured to said arms and composed of sheet metal sections bent at their ends to clamp said arms.

19. In testimony whereof I have signed this specification.

20 JEAN V. GIESLER.
